(57) **CLAIM**

The ornamental design for a coffee machine, as shown and described.

DESCRIPTION

FIG. 1 is a front perspective view of a coffee machine, showing my new design;

FIG. 2 is a rear perspective view thereof;

FIG. 3 is a front elevational view thereof;

FIG. 4 is a rear elevational view thereof;

FIG. 5 is a left side view thereof;

FIG. 6 is a right side view thereof;

FIG. 7 is a top plan view thereof;

FIG. 8 is a bottom plan view thereof;

FIG. 9 is a partial enlarged view of FIG. 1;

FIG. 10 is a partial enlarged view of FIG. 1;

FIG. 11 is a partial enlarged view of FIG. 1;

FIG. 12 is a partial enlarged view of FIG. 1;

FIG. 13 is a partial enlarged view of FIG. 2;

FIG. 14 is a partial enlarged view of FIG. 3;

FIG. 15 is a partial enlarged view of FIG. 3;

FIG. 16 is a partial enlarged view of FIG. 5;

FIG. 17 is a partial enlarged view of FIG. 5;

FIG. 18 is a partial enlarged view of FIG. 6; and,

FIG. 19 is a partial enlarged view of FIG. 7.

The dash-dot-dash lines are for an notating enlarged views;

all broken lines form no part of the claim design.
